UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

LEDGER SHEET.

1,415,904.

Specification of Letters Patent. Patented May 16, 1922.

Application filed April 30, 1919. Serial No. 293,641.

To all whom it may concern:

Be it known that I, JESSE A. B. SMITH, a citizen of the United States, residing in Stamford, in the county of Fairfield and State of Connecticut, have invented certain new and useful Improvements in Ledger Sheets, of which the following is a specification.

This invention relates to bookkeeping devices, and is herein illustrated as applied to a loose-leaf "Boston" ledger such as is used for bank-bookkeeping, and as especially adapted to be used in connection with an Underwood standard bookkeeping machine.

"Boston" ledgers comprise sheets which have horizontal rulings to divide them into spaces, so that there is a horizontal space between each two lines of ruling for each account on the ledger. These ledgers are also provided with vertical rulings to divide the horizontal spaces into columns for days, a column or columns for names, and other minor columns. Each day column is usually further divided into two or three subsidiary columns. As shown herein, these subsidiary columns are two in number, one to receive the items of charges and credits, or checks and deposits, the other column to show the current daily balance.

In order to enable a sheet of this character to be utilized to advantage in a typewriter bookkeeping machine, it is preferable to provide a column adjacent the daily balance column of each day, in which the "pick-up" balances can be written, while transferring the current daily balance into a computing register, preparatory to adding thereto or subtracting therefrom the next item to be entered in the checks-deposits column. A "pick-up" column, when thus utilized, enables the typist to visually verify the copying of the daily balance into the computing register, and by having the "pick up" column adjacent the daily balance column, the detection of errors in this copying is greatly facilitated.

Since these "pick-up" column entries are of no permanent value after the daily balance has been checked up, it is usually both a waste of space on the sheet written, and a waste of valuable storage room, to keep the written "pick-up" balances as a part of the

permanent records. Besides this, if the sheet is made wide enough to accommodate the "pick up" columns on its body, it becomes so wide as to be awkward to manage, and requires an exceedingly wide carriage in the computing machine which is to receive it.

With these limitations in mind, I have found it possible to design a ledger-sheet which shall contain an integral extension or portion adapted to receive such pick-up balances. This portion may be readily detached and discarded at the end of each day's work, or at the beginning of the succeeding day's work, or at such other time as is desirable. In carrying out this invention, I have found it advantageous to provide an extension flap attached to an edge of the ledger-sheet, said flap preferably extending from the side edge of the sheet last to be used over toward the opposite end of the sheet, and in a bank-ledger covering up all the day columns except the column for the first day. This flap or extension, along the edge which is adjacent the column for the first day, is adapted to receive the "pick-up" balances at the most effective position for that day, and, this flap being integral with the sheet, preserves its proper alignment with reference to the entries on the body of the sheet.

When the last entries have been made on the day column, for which the flap has served as a "pick-up" column the section of the flap which covers up the column to be used the next day, may be detached; being for this purpose preferably separated from the rest of the flap by a line of perforations. The flap advantageously contains a separate column or detachable portion to serve as a "pick-up" column for each of the other day columns.

In order to enable both sides of the ledger-sheet to be conveniently utilized, there may be provided two flaps, one attached at each end of the body of the ledger-sheet. Since these flaps are not kept for permanent use, and do not need to have edges which require sufficient strength to endure handling many times, the flaps may be made, if desired, of cheaper or lighter stock than the body of the ledger-sheets, and may be attached thereto by pasting. This will enable thinner stock to be used for the flaps, thus mate-

rially reducing the thickness of the ledger while in use, and also enabling money to be saved by the utilization of a cheaper stock than the fine ledger bond usually used for the body of such ledgers. The flaps may be attached either at the side edges or at the top and bottom edges of the ledger-sheet.

Other features and advantages will hereinafter appear.

10 In the accompanying drawings,

Figure 1 is a perspective view of one form of "Boston" ledger-sheet, showing the sheet at the close of Monday's business, ready to make the opening entry on Tuesday.

15 Figure 2 is a section through a sheet, showing how the flaps may be pasted upon the body of the sheet.

Figure 3 is a perspective view of the opposite side of the sheet shown in Figure 1, as 20 it is used on Monday of the succeeding week.

Figure 4 is a face view of the transfer column concealed at the right hand of Figure 3, shown detached, as it is used for copying onto the next sheet.

25 Figure 5 is a perspective view of a modified form of the sheet shown in Figure 1, in which the flaps are attached at the bottom and top edges.

Figure 6 is an enlarged view of part of 30 the sheet shown in Figure 5.

The ledger-sheet, herein shown, comprises a body portion 10, which has on each of the faces a name column 11 and a series of day columns 12, there being one day column 12 35 for each day of the week, as seen in Figure 1. Each day column 12 is further subdivided into a checks-deposits column 13 and a daily balance column 14, of which the former is adapted to receive the grouped 40 item entries as they come in, and the latter is adapted to always show, at its latest entry, the current working balance.

At the beginning of a day's work on Monday, the ledger-sheet showed a working daily 45 balance of \$2000, brought over from the preceding Saturday. Preparatory to entering the first item, which represents a deposit of \$500, the typist passes the folded sheet 10, with its flaps 15 and 16 lying against it, as 50 folded in Figure 1, around the platen of the bookkeeping machine, and copies out onto the extension 17 of the flap 16, which overlies the Tuesday column 12, the daily balance of \$2000 shown in the Monday daily 55 balance column; this being added at the same time into the "computing" register of the two-register bookkeeping machine, which is a type now on the market. One form of this machine embodying three registers is 60 illustrated in the patent to Hoyt, No. 1,280,228.

Then the typist positions the typewriter carriage to the checks-deposits column 13 of Monday, and writes therein the item \$500,

adding this item into the "computing" register, 65 and also into the "footing" register common in that type of machine. Then the typist positions the typewriter carriage to write in the daily balance column 14 of Monday, and copies therein the total shown 70 in the "computing" register, at the same time subtracting it out of that register, thus bringing the "computing" register to zero. The accuracy of this work is then proved by printing the usual clearance sign star. 75

Usually in ordinary bookkeeping accounts, there is only one deposit item and one check item for each day, unless checks or deposits come in at widely separated intervals during the day,—this resulting from the fact that 80 to assist in eliminating errors, the typist usually enters a large number of accumulated checks on a series of ledger-sheets at the appropriate columns and then enters a series of accumulated deposits on these sheets, in 85 this way minimizing the likelihood of entering a check as a deposit, or vice versa.

The entries so far described as being made this day are usually made in black. The last item, as shown entered this day, is an 90 item of checks amounting to \$1900. Preliminarily to entering this, the typist positions the typewriter carriage to copy out the daily balance of \$2500 from column 14 onto the extension 17, adding it into the 95 "computing" register aforesaid, and then repositions the carriage and writes out, advantageously in red, the item \$1900, subtracting this from both the computing and the footing register. Then the typist brings the 100 typewriter carriage to write in column 14, and copies into said column the total now shown in the "computing" register, namely, \$600, which represents the final balance for that day, and then prints the usual star; 105 this final balance being written in black.

At the close of the day's business, and preparatory to opening the books on Tuesday, the working daily balances of Monday are transferred in the ordinary manner to 110 the top of the daily balance column of Tuesday, the extension 17 having previously been detached along its perforated line 18, in order to uncover the Tuesday column. For working in Tuesday, the "pick-up" balance 115 column is written on the extension 19 from which the extension 17 was detached. The extensions of the flap 16 for the rest of the week are also utilized in the same manner, there being provided, immediately to the 120 right of Saturday, a narrow "pick-up" flap 20, which overlies a transfer balance column 21, said transfer balance column serving to receive balances transferred from the Saturday daily balance column. 125

The "pick-up" column flap 20 may be detached at the close of Saturday's business, before copying the transfer balances from

the Saturday daily balance column onto the transfer balance column 21; or the entries in the transfer balance column may be made by interposing a carbon-sheet between the flap 5 20 and the column 21. In either case, the flap 20 is detached along the perforated line 22, which hitherto has served as a hinge on which the extension 16, 17 swings, and the transfer balance column may be folded over 10 along the line 23, or detached along the line 23, and copied into the daily balance column 24 on the opposite side of the sheet shown in Figure 3, on which side of the sheet entries 15 may be made with precisely the same procedure, as described for the side shown in Figure 1.

The flap 15 is provided with perforations 18, like the flap 16, and is also provided with a Saturday "pick-up" extension column 20, 20 which overlies a transfer balance column (not seen), separated from the body of the sheet by a line of perforations 23. This transfer balance column which is on the back of the flap 16 is adapted to be detached and utilized for copying onto the sheets for the 25 next week's business, just as the transfer column 21 may be detached and so used.

In order to enable the sheets to be readily handled, it is customary to provide a loose 30 leaf file, or a binder which is adapted to bind them in any usual manner at the bottom.

To enable the flaps or extensions 15 and 35 16 to be made out of cheaper or lighter stock, if desired, they may be attached to the body of the sheet 10 by flaps or slips 26, which are adapted to be pasted down upon the edges of the sheet 10, the edges of the overlapping portions being advantageously along perforated lines such as the line 23.

The sheet, when finally filled up with entries and put away for storage, is reduced down to the size between the two lines 23, with the result that it then occupies no more 45 space or thickness than an ordinary handwritten ledger-sheet, since the pasted thicknesses are detached either when or after writing the transfer balances.

The sheet shown in Figures 5 and 6 has 50 one flap attached at the top along the line 28, instead of at the end of the sheet, and the other flap attached at the bottom along the line 29, but, like the Figure 1 sheet, is provided with lines of perforations 18 to 55 enable the flaps to be separated day by day. There are also provided perforations along the lines 28 and 29 to enable the flaps to be detached along the fold when separated along the line 18.

60 Variations may be resorted to within the scope of the invention, and portions of the improvements may be used without others.

Having thus described my invention, I claim:

65 1. The combination with a "Boston"

ledger-sheet, for use in a combined typewriting and computing machine in which computation of a transaction for any day involves the typing of the previous balance and the running of the same into the register, said ledger-sheet having day columns, 70 each including subsidiary columns for transactions and daily balances, of means to take the place of the "pick-up" columns which would otherwise be necessary in the ledger-sheet, said means comprising a "pick-up" sheet attached at one edge to and normally overlying the ledger-sheet, and comprising a plurality of temporary "pick-up" columns separated by lines of less strength so positioned as to coincide with the lines between the day columns, exposure of any day column in which it is desired to compute being effected by detaching the corresponding portion of the "pick-up" sheet and withdrawing it from overlying position.

2. A ledger-sheet adapted for use in a printing computing machine, divided into day columns, and having an extension attached thereto overlying all but one of said day columns, and including weakened lines along which the extension is adapted to be detached in strips covering one day column at a time.

3. The combination with a ledger-sheet 95 for use in a printing computing machine, said ledger-sheet being divided into day columns, each of which comprises subsidiary columns including a daily balance column and a transaction column, of an extension 100 of said ledger-sheet overlying, when in use, the day columns to the right of the one in use to receive "pick-up" entries from previous daily balance columns, said extension comprising "pick-up" column sections having lines of less strength therebetween, to permit the removal of used "pick-up" columns in succession and the consequent uncovering of underlying day columns.

4. A ledger-sheet adapted for use in a printing computing machine, divided into day columns, each day column comprising a plurality of subsidiary columns which include a daily balance column and a credit column, extensions of said sheet overlying the day 115 columns so that the one in use may have a "pick-up" column adjacent it adapted to receive "pick-up" entries from the daily balance column, and a weakened line at the edge of each extension to permit it to be detached 120 to permit the underlying column to be used, said extensions forming a flap extending from the vertical edge of said ledger-sheet.

5. A ledger-sheet adapted for use in a printing computing machine, divided into day columns, each day column comprising a plurality of subsidiary columns which include a daily balance column and a credit column, an extension of said sheet overlying each day column, and adapted to receive 125 130

“pick-up” entries from the adjacent daily balance column and to be detached in sections to permit the underlying columns to be used, said extensions forming a flap extending from the vertical edge of said ledger-sheet, a weakened line for each day column to permit the day columns on the ledger-sheet to be successively uncovered by detaching the extensions overlying the separate 10 “pick-up” columns, and a transfer balance column between said extensions and the body of the sheet, adapted to receive balances to be transferred to the sheet for the next week.

6. A ledger-sheet adapted for use in a printing computing machine, divided into day columns, an extension of lighter weight than the body of the ledger-sheet, to cover up the day column adjacent the one in use, to serve for receiving a “pick-up” balance 15 from the column in use, and to be detached to uncover the column beneath it, and a slip pasted to the edge of the ledger-sheet connecting the extension of the sheet and forming a hinge for it.

7. A ledger-sheet adapted for use in a printing computing machine, divided into day columns, an extension of lighter weight than the body of the ledger-sheet, to cover up the day column adjacent the one in use, to serve for receiving a “pick-up” balance from the column in use, and to be detached to uncover the column beneath it, a slip pasted to the ledger-sheet connecting said extension to the sheet, said slip where pasted to the sheet coinciding with a transfer balance column, and a weakened line between said transfer column and the remainder of the sheet to permit the pasted-on portion to be detached.

8. A ledger-sheet adapted for use in a printing computing machine, divided into day columns, an extension of lighter weight than the body of the ledger-sheet to cover up the day column adjacent the one in use, to serve for receiving a “pick-up” balance 40 from the column in use, and to be detached to uncover the column beneath it, a slip pasted to the ledger-sheet connecting said extension to the sheet, said slip where pasted to the sheet coinciding with a transfer balance column, a weakened line between said transfer column and the remainder of the sheet to permit the pasted-on portion to be detached, a similar transfer balance column at the opposite edge of the sheet, and a similar slip and connected extension pasted thereto and adapted to receive “pick-up” column 45 entries from day columns on the opposite side of the sheet.

9. A ledger-sheet adapted for use in a printing computing machine, divided into day columns, and having an extension attached thereto at one end and overlying all but one of said day columns, and including weakened lines along which the extension 60 is adapted to be detached in strips covering

one day column at a time, and a similar extension for the opposite side of the sheet attached at the opposite end thereof.

10. The combination with a ledger-sheet for use in a printing computing machine, 70 said ledger-sheet being divided upon each face into day columns, each of which comprises a plurality of subsidiary columns including a daily balance column and a transaction column, of an extension attached to the ledger-sheet at each edge and overlying, when in use, the day columns to the right of the one in use, said extensions comprising strips readily detachable along lines of less strength and constituting “pick-up” columns 75 coextensive with the underlying day columns, so that removal of a used “pick-up” column will expose a corresponding underlying day column.

11. A ledger-sheet adapted for use in a 80 printing computing machine, divided into day columns upon each face, each day column comprising a plurality of subsidiary columns which include a daily balance column and a credit column, an extension of 85 said sheet at each end overlying the day column adjacent the one in use, adapted to receive “pick-up” entries from the daily balance column and to be detached to permit the underlying column to be used, a slip extending from each vertical edge of said ledger-sheet connecting said extensions to the sheet, and weakened lines on said extensions 90 for each day column to permit the day columns on the ledger-sheet to be successively 95 uncovered by detaching the overlying “pick-up” column extensions.

12. The combination with a ledger-sheet for use in a printing computing machine divided into day columns upon each face, of 100 cover-sheets of lighter weight than the ledger-sheet positioned to cover the day columns to the right of the one first to be used, each cover-sheet comprising strips readily detachable along lines of less strength and constituting “pick-up” columns to receive 105 “pick-up” balances for use in computations in the day columns in use, and a slip at each end of the ledger-sheet pasted thereto and to the corresponding cover-sheet to connect 110 the same.

13. The combination with a “Boston” ledger-sheet, for use in a combined typewriting and computing machine in which computation of a transaction for any day involves the typing of the previous balance and the running of the same into the register, 115 said ledger-sheet having day columns, each including subsidiary columns for transactions and daily balances, of means to take the place of the “pick-up” columns which would otherwise be necessary in the ledger-sheet, said means comprising a “pick-up” sheet attached at one edge to and normally overlying the ledger-sheet, and comprising 120 125 130

a plurality of temporary "pick-up" columns separated by suitable lines of demarcation so positioned as to coincide with the lines between the day columns, exposure of any 5 day column in which it is desired to compute being effected by detaching the corresponding portion of the "pick-up" sheet along one

of said lines and withdrawing it from over-lying position.
